[57] CLAIM

The ornamental design for an electronic music stand, as
shown and described.

DESCRIPTION

FIG. 1 is a perspective view of the electronic music
stand showing my new design;
FIG. 2 is a front elevational view thereof;
FIG. 3 is a rear elevational view thereof;
FIG. 4 is a left side elevational view thereof;
FIG. 5 is a right side elevational view thereof;
FIG. 6 is a top plan view thereof; and,
FIG. 7 is a bottom plan view thereof.
The cords are shown broken away in FIGS. 1-3, 5 and
7 for convenience of illustration.

FIG. 1
